UNITED STATES PATENT OFFICE.

ADOLPH BERNAT AND ISAAC BERNAT, OF KANSAS CITY, MISSOURI.

ARCH SUPPORT.

Application filed November 16, 1921. Serial No. 515,504.

To all whom it may concern:

Be it known that we, ADOLPH BERNAT and ISAAC BERNAT, citizens of the United States, residing at Kansas City, in the county of Jackson and State of Missouri, have invented a certain new and useful Improvement in Arch Supports, of which the following is a specification.

The object of our invention is to provide an arch support which can be adapted for arches of different heights, which is simple, sanitary, cheap to make, durable, not liable to get out of order, which is easy on the foot, which is resilient, and in which the spring pressure which resists the depression of the arch may be varied as to strength and points of resistance.

The novel features of our invention are hereinafter fully described and claimed.

In the accompanying drawing, which illustrates the preferred embodiment of our invention,

Fig. 1 is a side elevation of our improved arch support.

Fig. 2 is a bottom view of the same.

Fig. 3 is a perspective view of the spring supporting plate.

Fig. 4 is an end elevation of the support.

Fig. 5 is an edge view of one of the spring seat plates.

Fig. 6 is a bottom view of the same.

Fig. 7 is a side elevation of the arch support, with one of the coil springs removed.

Similar reference characters designate similar parts in the different views.

1 designates a curved arch supporting member, preferably of flexible material, such as sole leather, and to which is imparted the general contour of a foot arch.

Secured to the under side of the member 1, preferably by screws 2, so as to be detachable, is a spring supporting flat plate 3, preferably of aluminum or sheet steel, having a plurality of seats for springs, each comprising, preferably, a pair of upwardly extending tongues 4 adapted to be encircled by the lower end of a coil spring.

In the drawing we have shown three pairs of tongues arranged in a longitudinal row. The center pair of tongues 4 are adapted to be inserted in the lower end of a vertical coil spring 5, the upper end of which rests against the under side of a circular seat plate 6 which in turn bears against the under side of the member 1.

Two other vertical coil springs 7 and 8 are adapted to be respectively fitted to the outer sets of tongues 4 and to have their upper ends rest respectively against two seat plates 6 corresponding in form and function to the seat plate 6 already referred to. Each seat plate 6 may be provided with two downwardly extending tongues 10 adapted to be inserted in the adjacent upper end of the adjacent coil spring. The tongues 4 and 10 serve to prevent lateral slipping of the coil springs.

The springs 5, 7 and 8 serve as a yielding resilient support for the member 1.

In the use of the arch support, one two or all of the springs may be employed. In some cases, where it is desired to gradually build up the arch of the foot, it may be advisable to use only the center-spring 5, or one or both of the springs 7 and 8, or one of these latter springs with the spring 5, as shown in Fig. 7. Then as the foot becomes accustomed to the support, an additional spring may be inserted.

To insert or remove the springs, it is but necessary to remove one of the screws 2, after which one or more of the coil springs may be inserted or removed, following which the removed screw may be re-inserted.

The spring supporting plate 3 is so disposed with reference to the member 1 as to rest upon the sole of the shoe. It is sufficiently flexible to conform to the contour of the upper side of the sole.

We do not limit our invention to the structure shown and described, as many modifications, within the scope of the appended claim, may be made without departing from the spirit of our invention.

What we claim is:—

An arch support comprising a flexible foot supporting member having an arched portion, a plate extending across said arched portion and adjacent to its ends attached to the under side of said member, and coil springs arranged in a longitudinal row and each removably mounted between said plate and said arched portion, substantially as set forth.

In testimony whereof we have signed our names to this specification.

ADOLPH BERNAT,
ISAAC BERNAT.
